Inventor:
BENJAMIN RICHARDS,

By Mitchell, Chadwick & Kent

Atty.

UNITED STATES PATENT OFFICE.

BENJAMIN RICHARDS, OF KENILWORTH, ILLINOIS, ASSIGNOR, BY MESNE ASSIGNMENTS, TO DETEX WATCHCLOCK CORPORATION, OF NEW YORK, N. Y., A CORPORATION OF DELAWARE.

RECORDING AND SUPERVISORY ATTACHMENT.

Application filed October 28, 1919. Serial No. 334,011.

To all whom it may concern:

Be it known that I, BENJAMIN RICHARDS, a citizen of the United States, residing at Kenilworth, in the county of Cook and State of Illinois, have invented certain new and useful Improvements in Recording and Supervisory Attachments, of which the following is a specification.

This invention relates to improvements in recording attachments. More particularly, it is here described as an attachment that may be applied to valves used in sprinkler systems arranged for fire protection for showing whether each valve is open or closed; but it may be used in other situations.

A sprinkler system ought to be so perfectly automatic that it will act without fail on the occurrence of the conditions under which it is expected to act. Yet fire losses are constantly happening because of the valve controlling the water supply of a supposedly automatic sprinkler system being closed at the time of fire. Such closures may happen properly in various ways, and also improperly, or happening properly may be allowed improperly to continue by neglect. The present invention provides for a record to show whether or not a valve is in service condition. It is a supervisory system showing automatically by the record the identity of the valve, to which the record refers, the fact that it is open or closed, whichever may be its normal condition, and showing the time at which the record was made. This object is accomplished by arranging in connection with the valve apparatus whose action is dependent upon the relative position of the valve members, i. e., whether they are in the position which they occupy when the valve is open, or in that occupied when it is closed; and by providing other apparatus for making a record which indicates valve identity and time; the operation of the latter apparatus by the watchman or other would be record maker being controlled automatically by the former apparatus. To accomplish this simply and surely, the invention provides a container with cover and lock for some part of the recording apparatus which must be reached and manipulated by the watchman in order to make the record. The lock is

controlled by the first mentioned apparatus, associated with the valve, and is automatically locked or unlocked by the shifting of the valve from normal to abnormal position, or the reverse. The cover is arranged to close automatically. When everything is normal, the record can be made showing normal condition, at any time, as by the watchman opening the cover and doing whatever is necessary with the part within, as, for example, taking the distinctive key which is hung on a chain within the container, according to one system with which the invention may be used, and applying it to his portable clock according to any of several systems already well known for watchmen's clocks. But if at any time before his visit the valve has been set in abnormal position, and so continues, he finds the door of the container automatically locked, and cannot make a record. The absence of record relating to a particular valve, at the time and on the card provided for it, shows either that the watchman has not visited the valve, or that the valve is in abnormal condition. Either situation constitutes a warning.

While the general purpose may be accomplished in various ways, the present application has especial reference to specific means first shown in my co-pending application Serial No. 166,788, wherein means on the valve stem, and moving when it moves, controls by a lock the accessibility of the part of the recording apparatus which has to be used in order to make a record; and it is intended that the patent shall cover, by suitable expression in the appended claims, whatever features of patentable novelty exist in the features disclosed in this respect.

In the accompanying drawings:

Figure 1 is an end elevation of apparatus embodying the invention, in section on the line 1—1 of Figure 2;

Figure 2 is a side elevation of the same, partly in section;

Figure 3 is a fragmentary end elevation showing application to a magneto or electrical system;

Figure 4 is a side elevation of a modification, partly in section on the line 4—4 of Figure 3;

Figure 5 is a section on the line 5—5 of Figure 4; and

Figure 6 is a section on the line 6—6 of Figure 5.

Referring to the drawings, the yoke of the valve is marked 1, and the valve stem guided thereby is marked 2. On that stem is a cylindrical enlargement or boss 3, having a sloping abutment 40 which is the actuating means of the control apparatus which will first be described. A box 4, preferably metallic, provided to hold this, is adapted to be made fast to the yoke 1 by a strap or bridge 5 on the remote side of the yoke, to which the box 4 is connected by bolts 6 having screw nuts 7 within the box. The heads of the bolts may be counter-sunk flush with the surface of the strap 5, so as to afford no hold to a tool for unscrewing them. The box 4 has a cover 8, fastened by screws and a perforated tongue 10 which passes through a hole in the cover like a staple, so that the cover may at this place be fastened in its closed position with any suitable device, such as a padlock, or, as illustrated, with a metallic seal. This provides so that the box 4 and its contents can be set in any desired predetermined position on the yoke 1, without it being possible for anyone to remove it, or change its position, without first opening the sealed box. For the same reason the mechanism within it is inaccessible to anyone who might wish to tamper with it, except as the part of the recording apparatus contained in compartment 27 may be reached through a door 29, which forms part of the cover, in the course of ordinary operation of the device. Within the box 4, a lever is provided, supported on a pivot 13 conveniently held in two internal bosses 14, or otherwise suitably held, and having an arm 12 which extends through a hole in the wall into the space between the two members of the yoke 1 at such an angle and position that it can bear against the valve stem 2 and with sufficient play so that it can ride on its surface or upon the surface of the boss 3 on the stem, the edge of the boss having the cam surface 40, if desired, for shifting the lever. The other arm of this lever is marked 15, extends into compartment 27, adjacent to the cover 8, where it has a latch or hook 16 adapted to engage a post 29' on the door 29 of this compartment which door may be conveniently hinged at 9. A projection 18 extends from some convenient part of the lever and is engaged by a spring 19, which presses upon it so as to force the outer arm of the lever 12 toward the axis of the valve stem 2, so that whatever be the position of the valve stem, with the valve open or closed or in any intermediate position, the lever 12 is pressed against the stem. Obviously, therefore, when the boss 3 is opposite the lever arm, the lever

will be held with the spring 19 in a state of compression and with the latch 16 at its limit of travel into the compartment 27, which is its open position. The parts are so designed and set that when the valve is open the lever is engaged on the boss of the stem, and so that when the lever is thus at its limit of travel its latch 16 does not engage the door; but when the lever is not engaged on the boss of the stem the latch does engage the door and hold it firmly locked. Within the compartment 27 is a watchman's key 30 of any ordinary or suitable type, by which a watchman can make a record on his portable watchman's clock. He cannot open the door 29 to use this key unless the position of the valve stem 2, which corresponds to the position of the valve which is being supervised, has set the latch 16 open, and so an absence of record by him indicates that the valve is closed, or at least that it is not open to the prescribed degree, or that he has not visited the station.

Figure 3 indicates how the invention may be applied to a recording system using a magneto or other fixed electrical system connecting through wires 32 with a central recording appliance, (not shown) according to any ordinary system now in use, or some other suitable system. In that case, there is no key 30 but an arbor 31 is arranged within the box with a magneto indicated as being within the compartment which can be operated at will whenever the door 29 can be opened so as to insert the tool or key therefor. For these purposes, the arbor takes the place of the key therefor, being the device which needs to be turned in order to make the record. Obviously, any other sort of electrical recording or signalling device might be substituted having the part that requires manipulation located under protection of the automatic lock.

The device by which the position of the valve stem controls the recording may take various forms. In Figure 4, for example, it is illustrated as a reduction in diameter of the valve stem or notch cut therein; as at 3', with sloping cam shoulder 40' constituting the abutment. In that case, the connected lever, spring and latching parts are rearranged as requisite. In either event, whether the lever controlling device be a boss, as in Figures 1 and 2, or a depression, as in Figure 4, it may be arranged at such a position on the valve stem, and the lever will be so arranged with respect thereto, and so controlled by a spring, that it will be moved into position for permitting a record only when the valve is open to a degree which is predetermined by the location of this lever controlling device on the valve stem. And this in turn will be located only at a place that corresponds to what is

deemed a sufficient opening, and may operate to lock the apparatus on one or two turns of the valve wheel. If a boss be used, as in Figures 1 and 2, this may preferably take the form of a collar fastened on the stem by suitable means, such as by soldering.

The device thus combines in itself automatically a record of the watchman's faithful attention to duty in visiting the assigned 10 parts of the premises under his care, and a record that the valve at each such place is open, together with the time of such visit and condition. He cannot make his record unless he visits the place, nor can he make it even then, unless the valve is open; and any 15 standard watchman's apparatus of tested reliability can be used to record the time and station.

Figures 4, 5, and 6 represent a modification 20 in which the key 30 automatically returns to its place in the compartment 27'. To this end, the box 4' may be suitably secured on the yoke 1 of the valve and may have a compartment arranged to enclose the 25 depending key behind its door 29''. In this case, the arm of the lever which engages the valve stem is marked 12' and the arm which latches the door 29'' is marked 15'. The flexible tie 33 which holds the key 30 is of 30 such length that the depending key does not reach below the bottom of the receptacle; and the side walls 27'' of the receptacle are flaring, as seen in Figure 6, and should be sufficiently flaring so that however the key is 35 dropped it will swing down and into the receptacle, and be caught therein by the depth and narrowness of the rear part of the receptacle, in order to avoid being caught by the descending door. In this case, the fastening 40 of the key and the lock of the door are represented separated from that part of the compartment where the key hangs by a partition held in place by a sealed screw 35.

I claim as my invention: —

45 1. The combination of a valve having an actuating part with a recorder adapted to be actuated independently of the valve, and locking means controlled by the valve actuating part for preventing actuation of the recorder.

50 2. The combination of a valve having an actuating part with a recorder adapted to be manually actuated independently of the valve, an element which normally must be moved as a preliminary to actuation of the recorder, and locking means actuated by the valve actuating part and locking the said element when the valve is actuated to move it from normal position.

55 60 3. The combination of a valve having an actuating part with a recorder adapted to be actuated independently of the valve, a container for an actuating part of the recorder, and locking means between said valve actuating part and the container whereby the

65 container is locked and actuation of the recorder prevented when said valve actuating part is moved from its position which corresponds to normal position of the valve.

70 4. The combination of a valve having an actuating part with a recorder adapted to be actuated independently of the valve; a box having a door and lock therefor enclosing an actuating part of the recorder; and means whereby the valve actuating part by its 75 movement to actuate the valve operates said lock.

75 5. A supervisory mechanism comprising in combination, a valve, a manually operable instrument adapted to be operated by a 80 watchman in making his rounds, a container for said instrument, a closure for said container, means for operating said valve, and means controlled by said first named means for controlling said closure.

85 6. In combination, a valve, a circuit controlling device adapted to be operated by a watchman in making his rounds, and means for preventing the watchman from exercising control of the circuit controlled by said device when the valve is in abnormal condition.

90 7. The combination of a valve, a recording device having an actuating part, a closure for said actuating part, and means for 95 securing said closure except when the valve is in a predetermined position, said means being operated by the movement of the valve.

95 100 8. A supervisory mechanism for a sprinkler and other systems comprising a supply, a valve in said supply, a container for an electrical device for actuating a signal, in combination with means set by the actuation of said valve for controlling the access 105 to said device.

105 110 9. A supervisory mechanism comprising a supply, a valve adapted to shut off said supply, electrical means for actuating a signal, in combination with mechanism set by the actuation of said valve, and means operated by said mechanism to render said electrical means inaccessible for actuating a signal.

115 10. The combination with a normally open valve, of a magneto normally accessible for making a record, means for rendering said magneto inaccessible, and means adapted to actuate the aforesaid means when the valve is moved toward its closed 120 position.

11. In combination, a valve, a manually operable electrical device, and means controlled by said valve for preventing operation of said device unless said valve is in a 125 predetermined position.

12. The combination with a normally open valve, of an electrical device normally accessible for making a record, means for rendering said electrical device inaccessible, 130

means adapted to actuate the aforesaid means when the valve is moved toward its closed position, and means adapted to return the same to its initial position when the valve is brought back to normal.

13. In combination, a valve, recording means comprising a stationary instrument and a tool for engaging the same to produce a record, and means comprising an obstruction for the stationary instrument for preventing manual engagement of said tool with said instrument when the valve is in an abnormal condition.

14. In combination, a valve, recording means comprising an instrument and tool at least one of which is stationary, said tool being normally adapted to engage said device to produce a record, an obstruction to such engagement movable from a position in which it permits such engagement, and means controlled by said valve for controlling said obstruction.

15. In combination, a valve, a manually operable circuit-controlling device, and means controlled by said valve for removing the control of the circuit from the operator when said valve is in a predetermined position.

16. A supervisory mechanism as set forth

in claim 1 in which the recorder comprises a manually operable magneto.

17. A supervisory mechanism as set forth in claim 2 in which the recorder comprises a manually operable magneto.

18. In combination, a valve, a recorder controlling electric circuit, a manually operable device adapted to be operated by a watchman in making his rounds for periodically controlling said circuit, and means controlled by said valve for affecting record-producing use of said device.

19. In combination, a valve, a recording instrument, electrical means controllable by a watchman in making his rounds for causing said instrument to produce a record, and means controlled by said valve for affecting the record so produced.

20. The combination of a valve; a device for making a record, and interlocking mechanism engaged by a moving part connected with the valve and affecting the operation of the recording device; said interlocking mechanism being operated by movement of said moving part.

Signed at Boston, Massachusetts, this twenty-seventh day of October, 1919.

BENJAMIN RICHARDS.
